UNITED STATES PATENT OFFICE.

JUAN S. L. BABBS, OF NEW ALBANY, INDIANA.

IMPROVEMENT IN DOVETAILING-MACHINES.

Specification forming part of Letters Patent No. 55,223, dated June 5, 1866.

To all whom it may concern:

Be it known that I, JUAN S. L. BABBS, of New Albany, in the county of Floyd, in the State of Indiana, have invented an Improvement in Dovetailing-Machines; and I do hereby declare that the following, taken in connection with the drawings which accompany and form part of this specification, is a description of my invention sufficient to enable those skilled in the art to practice it.

This invention is an improvement designed to be incorporated into the dovetailing-machine patented under the number 41,992 to S. E. Hartwell on the 22d day of March, 1864.

In the fronts and backs of drawers or other pieces corresponding thereto the cutters of said Hartwell's machine leave a semicircular termination of the mortises, while the tenons cut by Hartwell's machine, organized as described in his said patent, are not rounded to fit or to approximate to fit the circular termination of the mortises.

To round the tenons so that they will fit or approximate to the semicircular termination of the mortises is the object of my invention, which consists in the combination, with the conical cutters and the slide by which the stock is presented to the action of the cutters, of a secondary carriage or stock-holder, when arranged to convey the stock with the tenons formed thereupon partially around the cutter, by which means the angles are removed from the part of the tenons coming innermost in drawer, box, or similar work, the tenons being thus rounded to fit or approximate to a fit so that the tenons may be pressed fully into the semicircular terminations of the mortises.

Figure 1 of the drawings shows, in plan, an apparatus embodying my invention, exhibiting the position of the carriage conveying the stock to the cutters in the position it has after the stock has been passed over the cutters, forming full angled dovetailed tenons. Fig. 2 is a diagram showing the position of parts after completing the rounding of the tenons by moving them around the cutters. Fig. 3 is a sectional plan of the tenons, the section being taken in the line of their junction with the piece from which they are formed, this view showing the condition of the tenons as

left by the Hartwell machine before referred to. Fig. 4 is a view similar to Fig. 3, but shows the tenons as changed in form by the operation of my addition to Hartwell's machine.

As in Hartwell's patent, C C represent the cutter-heads, E the carriage by and on which the stock is carried to the action of the cutters, and F F are the ways on which the carriage E moves. Properly located with respect to the cutters is a clamp-box, a, provided with means for holding pieces on the ends of which the pins or tenons are to be cut, such means being represented by the screw b. This box is mounted at each end by ears c on the crank-pins d fixed in the pieces e, which are journaled to the carriage or slide E, the pieces e being connected so as to move together by their arms e' e' and the link f.

Operation: The stock for the drawer ends or other similar pieces being in readiness, the carriage E, with the clamp-box thereon, is removed from vicinity of the cutters, or so that in the apparatus shown in the drawings the edge 1 of the carriage is brought near the edge 2 of its support. The position of a, and the parts therewith connected, with reference to carriage E, being made that seen in Fig. 1, the stock requiring the formation of tenons thereon is clamped in box a by screw b, and then the carriage E and box a are moved in the direction of the arrow, Fig. 1, till the cutters form the dovetail grooves through the stock, this leaving the tenons required and the parts in the position shown in said figure. The cutters having now formed clear paths through the stock, the clamp-box is moved by the operator from position seen in Fig. 1 to that shown in Fig. 2, the lever g being employed by the operator to move the parts.

I claim—

The combination, with the conical cutters and the carriage by which the stock is presented to the action of the cutters, of a secondary carriage or stock-holder, arranged to operate substantially as set forth.

JUAN S. L. BABBS.
